United States Patent Office.

WILLIAM L. HUBBELL, OF BROOKLYN, NEW YORK.

Letters Patent No. 69,996, dated October 22, 1867.

IMPROVEMENT IN CAN-OPENER.

The Schedule referred to in these Letters Patent and making part of the same.

TO ALL WHOM IT MAY CONCERN:

Be it known that I, WILLIAM L. HUBBELL, of Brooklyn, in the county of Kings, and State of New York, have invented, made, and applied to use a certain new and useful Improvement in Can-Openers; and I do hereby declare the following to be a full, clear, and exact description of the said invention, reference being had to the annexed drawing, making part of this specification, wheruin—

Figure 1 is a longitudinal section of said can-opener.

Figure 2 is an inverted plan of the same, and

Figure 3 is an elevation of the knife separately.

Similar marks of reference denote the same parts.

Can-openers have heretofore been made, in which the sheet metal is cut by the action of a knife, of a semi-circular form, and a cutting tool has been employed to perforate and raise the edges of the sheet metal forming the end of the preserve-can. These devices, however, are costly, and some of them are liable to slip when in use.

The nature of my said invention consists in an opener for sheet-metal fruit and preserve-cans, formed of a lever, having an adjustable spike, so as to vary the diameter of the disk of sheet metal that is cut out by a peculiar knife, that is placed diagonally, so as to cut under and lift up the said disk, and prevent the knife slipping out while in use, and cause the said opener to retain its hold upon the disk of sheet metal until it is taken from the can.

In the drawing *a* is a handle or lever, curved at *b*, and *c* is a spike that is made with a tapering perforating point, and with a screw-shank. Through the lever *a* are two or more screw-holes to fit the screw-spike *c*, so that it may be placed nearer to or further from the cutter *d*, for forming a larger or smaller opening in the can.

The cutter *d* is set into a recess, formed by grooves, on the edges of the lever *a*, at the curved part *b*, so that one edge of the cutter projects below the under side of the lever at an inclination, as shown, so that the cutter is prevented from rising by its being below, and inclining inwards under the edge of the disk that is being cut out by revolving either the can or the opener. The edge of the cutter *d* is rounded outwardly, so as not to draw the spike *c* out of its position, and I form the two ends of the cutter *d* with correspondingly-shaped edges, so that the same can be changed end for end.

The mode of using this can-opener will be apparent, viz, to thrust the spike into the middle part of the can at the end, and rotate either the can or the opener, after the cutter *d* has been made to penetrate the sheet metal.

What I claim, and desire to secure by Letters Patent, is—

The can-opener, formed with the cutter *d*, made as described, and placed diagonally, in combination with the spike *c*, as and for the purposes set forth.

In witness whereof I have hereunto set my signature this sixteenth day of August, 1867.
